UNITED STATES PATENT OFFICE.

CHARLES H. MOORES AND WAINWRIGHT B. GERVAIS, OF CHICAGO, ILLINOIS.

STORAGE VAULT.

Application filed May 15, 1922. Serial No. 560,901.

To all whom it may concern:

Be it known that we, CHARLES H. MOORES, a citizen of the United States, residing at Chicago, in the county of Cook and State 5 of Illinois, and WAINWRIGHT B. GERVAIS, a citizen of the United States, residing at Chicago, in the county of Cook and State of Illinois, have invented certain new and useful Improvements in Storage Vaults, of 10 which the following is a specification.

This invention relates to improvements in storage vaults and more particularly to vaults of the type used in warehouses for the storage of household goods and the like.

15 In a prior pending application, filed August 15, 1917, Serial No. 186,270, Charles H. Moores, one of the joint inventors herein, describes a method of storing involving the provision of individual vaults of the 20 size of the body of the ordinary moving van, these vaults being transported on flat-top trucks or the like, to the place where the goods are to be received and returned to the warehouse in like manner, after being 25 packed, sealed, etc. At the warehouse the vaults are removed from the trucks and placed in suitable compartments especially designed therefor. This method obviates the necessity of removing the goods from 30 a van or the like and repacking them in the warehouse, such as is the practice according to the old method.

One object of the present invention is to 35 provide a portable storage vault which shall be especially adapted to the practice above described. Another object is to provide a vault of the character described which shall be constructed of sheet metal, reinforced in such wise as to render the same very 40 strong and durable, while at the same time providing a construction which is light in weight. A further object is to provide in such a vault, ventilators adapted to automatically close in the event of a fire within 45 the vault so as to prevent spreading of the same and at the same time preventing the further circulation of air into the vault. Another object is the provision of automatically operable temperature controlled means 50 for the generation of carbon dioxide, or other heavier-than-air gas, within the vault in the event of fire.

55 Other objects or advantages will be apparent from the following description taken in connection with the accompanying draw-

ings wherein one form of the invention is illustrated.

In the drawings—

Figure 1 is a front elevation of a storage vault constructed in accordance with the 60 present invention.

Fig. 2 is a sectional view taken on the line 2—2 of Fig. 1.

Fig. 3 is a view of the structure shown in Fig. 2 looking in the direction of the 65 arrow shown in said figure and illustrating the ventilators in closed position.

Fig. 4 is a side elevation of one of the storage vaults.

Fig. 5 is a sectional view taken on the 70 line 5—5 of Fig. 4; and

Fig. 6 is a sectional view taken on the line 6—6 of Fig. 5.

Referring more in detail to the drawings, 75 the vault is shown as comprising top, bottom, side, and end sections, all of sheet metal construction. The bottom 10 of the vault, is crimped longitudinally as at 10^a to provide channel-like ribbed portions 80 which serve to stiffen the bottom and to impart rigidity thereto. At its edges the bottom section 10 is crimped upwardly to provide, in effect, a flange 10^b, said flange extending completely around the bottom section. Suitable angle irons 11 are riveted 85 or otherwise secured to this raised flange 10^b of the bottom section. The two side sections 12 and 13 and the back section 14 are 90 of comparatively heavy gauge corrugated sheet metal, the corrugations extending vertically from top to bottom of said sections. At suitable intervals these corrugated sections 12, 13, and 14 are crimped as at 12^a, 13^a and 14^a respectively to provide ribs 95 of channel configuration in cross section extending from one edge of the other thereof, also in a vertical direction. These crimped portions serve as stiffening or reinforcing ribs. Secured against angle irons 11, which 100 as above described are riveted to the flange 10^b of the bottom section 10, is another set 105 of angle irons 15, the latter being so positioned that one leg thereof extends outwardly away from the bottom section to form a ledge or shoulder 15^a adapted to underlie the lower edges of the side and back sections previously described. After 110 these latter sections have been mounted in upright positions upon the ledge or shoulder 15^a, they are securely clamped adjacent

their bottom edges between the upright leg of the angle iron 15 and an outer band composed of a series of metal straps or bars 16 by means of rivets or the like 16^a.

- 5 The top section of the vault is shown at 17 and is preferably in the form of a flat sheet of metal down turned at its edges to provide flange 17^a. Spot welded or otherwise secured to the under surface of the top 10 section are a plurality of angle bars 17^b, the latter being spaced inwardly slightly from the flange 17^a so as to provide a groove for the reception of the upper edges of the side, back and front sections of the vault when 15 the cover is positioned. If desired, the cover may be held firmly in position by means of rivets 17^c or the like, which extend through the flanges 17^a and 17^b and the upper edges of the corrugated side and 20 end sections of the vault as shown more clearly in Fig. 5. Also secured against the under surface of the top section 17 are a plurality of transversely extending angle bars 17^d. These may also be attached to the top 25 by means of spot welding or the like and serve as reinforcements or stiffening ribs. Further, in connection with the top section, it is to be noted that the same is provided with a slight pitch in opposite directions 30 from its transverse center line so as to provide for rapid draining when the vault is exposed to the weather. Along its front edge the top section is provided with a small downwardly inclined water shed 17^e.
- 35 Vertically extending angle irons 18 are provided to reinforce and stiffen the corner edges of the vault where the side and end sections come together, the meeting edges of said sections being riveted or otherwise 40 securely fastened to these angle bars, as shown more clearly in Fig. 6. If desired, the bottom corners of the vault may be further reinforced by gusset plates, or the like as at 19. The vault in its entirety may also 45 be further reinforced or stiffened by means of channel bars 20, one for each of the side and back sections being shown in the drawings, these bars extending preferably at right angles to the corrugations and substantially midway of the bottom and top 50 edges of said sections, as shown more clearly in Fig. 5. These bars may be secured in position in any well-known manner.
- The front section of the vault comprises a 55 plurality of outwardly swinging doors 21, suitably reinforced and hinged along their outer vertical edges as at 21^a. Suitable locking mechanism designated generally by reference character 22, is provided for preventing access to the vault after the same 60 has been packed and stored. The mechanism comprises, briefly, a circular plate 22^a having pivotally attached thereto oppositely extending locking bars or rods 22^b, which 65 engage through apertures in brackets 22^c

at the top and bottom of the vault respectively. The circular plate 22^a is provided with an operating lever 22^d exteriorly of the vault by means of which the plate 22^a may be rocked in either direction to project 70 or retract the bars 22^b to thus lock or unlock the doors. When the doors are locked, the lever 22^d is in the position shown in Fig. 1, resting downwardly upon bracket 22^e, the latter and lever 22^d being provided with 75 alined apertures adapted to be engaged by the hasp of a padlock or the like 23.

Extending transversely across the bottom section of the vault are a plurality of channel bars 24 disposed with their backs against the bottom face of said section and with their channels disposed downwardly. Secured within the channels of these bars 24, adjacent their opposite ends are a plurality of brackets 24^a which carry axles 25, the latter extending parallel with respect to the channel bars 24 and terminating short of the ends of the latter. Small flanged wheels 25^a are carried adjacent the ends of axles 25 and inwardly of the brackets 24^a, these 80 wheels being adapted for engagement with suitable rails 26 upon which the vaults are moved from place to place in the warehouse. It is also contemplated to provide tracks such as just described on the vehicles used 85 for conveying the vaults from and to the warehouse so that at all times the said vaults will be supported on tracks, thus rendering the same easily movable.

Secured to the interior of the side sections and preferably to the crimped portions 12^a, and 13^a respectively are a plurality of hasps or the like 27. To these hasps are attached sections of strap 28 provided with the ordinary buckle etc. 29, the purpose of these 100 straps being to provide a barrier for the goods after the same have been packed into the vault. A pair of these straps is provided, at the front end of the vault immediately inside the doors, these being used 105 when the vault is completely filled. When the vault is only half or three-quarters filled, however, the pairs of straps in the middle of the vault or those immediately forward thereof may be used. It will also be observed that these straps when buckled, act 110 to reinforce the side sections, counteracting all buckling and bulging tendencies.

Hand grips 30, or the like, may be provided at opposite sides of the vault to facilitate moving the same from place to place. To further facilitate moving of the vault one or more elongated hooks 32 may be provided, one being shown in the drawings attached at its rear end to a suitable bracket or angle bar 32^a carried by the bottom section of the vault. From this bracket 32^a the hook extends forwardly and is supported intermediate its ends between front channel bar 24 and the bottom surface of section 10. 130

The front hooked end of the rod terminates substantially flush with the front door section of the vault so as to be readily accessible.

5 In each of the doors 21 there is provided a screened ventilating opening 31. Cooperating with each of these openings is a pivoted shutter or the like 31^a, these shutters being normally held in the raised position, 10 as shown in Fig. 1, by means of wire or the like, 31^b, and interposed fusible link 31^c. The fusing point of the metal of which link 31^c is constructed is so regulated that upon a marked rise in temperature, such as would 15 be occasioned by a fire, or the like, the said link is melted or broken allowing the shutters 31^a to fall by gravity, thereby closing the ventilating openings, as shown in Fig. 3. A suitable stop 31^d is provided to limit the 20 downward movement of the shutters.

As a further precaution against damage to goods which may be stored in the vault as a result of fire or the like, means is provided therein for the automatic generation 25 of carbon dioxide, or other heavier-than-air gases upon a marked rise in temperature. This means, in the present disclosure, comprises a cylindrical container 33, riveted or otherwise secured against the bottom surface 30 of the top section 17 of the vault. In the bottom of this container 33 a suitable dry chemical 33^a is placed and covered with some water proof material so as to prevent deterioration such as would result by exposure 35 to the atmosphere. Suspended within the container 33 immediately above the dry chemical, is a small fragile receptacle 33^b which contains the liquid chemical. The side walls of the container immediately adjacent the upper edge thereof are apertured 40 as at 33^c. Projecting into the container 33 but normally held out of contact with fragile container 33^b is a sharp pointed spring pressed plunger 33^d held in its normal position by means of a collar 33^e and fusible link 33^f. The fusing point of the metal link 45 33^f is also regulated so that upon a marked rise in temperature within the vault, the link will be melted or broken, thus releasing 50 the plunger 33^d whereupon the latter will be shot forward by the spring, the pointed

end thereof fracturing the receptacle 33^b and allowing its liquid contents to flow into contact with the dry chemical 33^a, thereby generating the heavier than air gas. The latter 55 will be forced outwardly through apertures 33^c into the vault and extinguish the fire. In practice it is preferred to regulate the fusing points of the metals of which links 31^c and 33^f are made so that the former will be 60 broken slightly in advance of the latter. In this way the circulation of air into or through the vault will be obstructed prior to the release of the fire extinguishing gas, 65 thus rendering the latter more effective. 65

As will be obvious to those skilled in the art, the present improvements are susceptible of various changes and modifications without departing from the spirit of the invention and accordingly it is not desired to limit 70 the same except where limitations appear in the appended claims.

What we claim is—

1. A portable storage vault of sheet metal construction, comprising vertically corrugated side and back sections, a bottom section, said bottom section being crimped upwardly around its edges to provide a flange, angle bars secured to said flange and surrounding said section, a second set of angle bars secured to said first named bars in such wise as to form an inverted T in cross section, the outer arm of said T underlying the lower edges of said side and back sections, and an outer band of bars surrounding 80 said sections in the vicinity of said bars. 75

2. A portable storage vault of sheet metal construction, comprising top, bottom, side and back sections, said bottom section being crimped upwardly around its edges to provide a flange, angle bars secured to said flange and surrounding said section, a second set of angle bars secured to said first named bars in such wise as to form an inverted T in cross-section, the outer arm of 90 said T underlying the lower edges of said side and back sections. 95

In testimony whereof, we have subscribed our names.

CHARLES H. MOORES.
WAINWRIGHT B. GERVAIS.
